Inventor:

Werner Lindner.

UNITED STATES PATENT OFFICE.

WERNER LINDNER, OF BEUTHEN, GERMANY.

BLASTING-BORE CLOSURE.

Application filed November 17, 1926, Serial No. 148,981, and in Germany July 26, 1926.

This invention relates to improvements in blasting closures. Said closure is preferably used in combination with a water filling of one part of the blasting bore and comprises a 5 plug proper having a longitudinal bore and means to operate like a non-return valve. Said closure bringing about a saving in blasting material and affording perfect safety while the blasting work is carried out. The 10 blasting bore is, to that effect, filled in the manner shown in the accompanying drawing, in which also the blasting bore plug is illustrated diagrammatically and by way of example. Figure 1 is a longitudinal section 15 through a filled blasting bore ready for use, Figure 2 is partly a side view of, and partly an axial section through a blasting bore plug designed according to this invention, this figure being drawn to a considerably increased scale relatively to Figure 1, and Figure 20 3 is an end-view of said plug.

On the drawing, 1 (Fig. 1) denotes the finished blasting bore, 2 the blasting substance introduced into its rear portion, 3 the fuze 25 for this substance, 4 a fuze cord, and 5 a stopper consisting of loam and preventing the blasting substance 2 from leaving its place, as well as from getting moist. The 30 free end of the blasting bore is closed by a plug 6 which is preferably conical and consists of wood or another suitable material. The details of this plug are shown in Figs. 2 and 3. The blasting bore end is preferably so much enlarged that the plug 6 can be provided with a packing 11 of plastic loam for 35 tightening it in the blasting bore end. The plug 6 is provided with an axial channel 7 through which water can be, and is, introduced, may be by means of an ordinary syringe, into the blasting bore space 1^a between the stopper 5 and the plug 6 until this space is completely filled. The water will be retained in said space in most cases already by the pressure of the atmospheric air; only if 40 gas finds access into the blasting bore the water will be forced out of it, or of the space or chamber 1^a respectively. In view of this possibility or from reasons of safety generally,

a piece of rubber film 8 is drawn over the inner face of the plug 6, as well as over the 50 rear end of the plug channel 7, and is secured in place by a cord 9 wound round in a peripheral groove 10, as shown especially in Fig. 2. This simple elastic closing member (8) permits the introduction of the water 55 into the chamber 1^a, but prevents the water from leaving said chamber in that it acts as a non-return valve. Of course, also another type of non-return valve could be used.

When the blasting bore 1 has been filled 60 and prepared in the manner stated, and the blasting substance 2 is exploded, a very strong pressure is suddenly exerted upon the water which not only has a great inertia but also cannot be compressed, the result being 65 that the action of the blasting substance is greatly intensified by that water pressure in that it presses upon the blasting bore wall and rends the mineral. On the other side, however, the water forms a particularly effective protection from the dangerous explosion of hydrocarbons, as well as from coal dust, because it extinguishes at once the explosion flame.

I claim:

1. A plug for closing the open end of a blasting bore, comprising, in combination, a plug proper having a longitudinal bore, and means provided at the inner face of this plug and adapted to operate like a non-return 80 valve, for the purpose set forth.

2. A plug for closing the open end of a blasting bore, comprising, in combination, a plug proper having a longitudinal bore, and a non-return valve provided at the inner end 85 of said bore, for the purpose set forth.

3. A plug for closing the open end of a blasting bore, comprising, in combination, a plug proper having a longitudinal bore, and a rubber-film attached to the rear end of said 90 plug and covering the rear end of said bore and being adapted to operate as a non-return valve for the said bore, substantially and for the purpose set forth.

In testimony whereof I affix my signature.
WERNER LINDNER.
